UNITED STATES PATENT OFFICE.

HARRY H. SHULTS, OF GOWANDA, NEW YORK.

DOOR HINGE.

1,410,840.

Specification of Letters Patent. Patented Mar. 28, 1922.

Application filed January 24, 1919. Serial No. 272,839.

To all whom it may concern:

Be it known that I, HARRY H. SHULTS, a citizen of the United States, residing at Gowanda, in the county of Cattaraugus and State of New York, have invented certain new and useful Improvements in Door Hinges, of which the following is a specification.

This invention relates to an improvement in lockers of the individual type and of metallic construction.

The object is the provision of a particular hinge structure, whereby the hinge parts or members may be readily assembled with the metallic parts of the locker and as readily disconnected therefrom, the arrangement lending itself to an economical construction without in any degree sacrificing any of the advantages of the usual riveted hinge.

The invention is illustrated in the preferred arrangement of details in the accompanying drawings, in which:—

Fig. 1 is a perspective view of a metal locker having a door hinged thereto in accordance with this invention.

Fig. 2 is an enlarged transverse section of the locker in a line with one of the hinges.

Fig. 3 is a broken perspective, showing the arrangement of the hinge members.

Fig. 4 is a perspective of the hinge members, shown separated.

The locker illustrated by the drawings is of metallic construction throughout, and comprises side walls 1, a rear wall 2, a top section 3, and a bottom section 4. The respective corner strips of the locker are of angle formation, as at 5, and the side walls and rear wall are riveted to the respective portions of these angle strips. The open front is closed by a door hingedly supported in accordance with this invention. The door, indicated by the numeral 14, is preferably a single piece of sheet metal of a size to fit the door opening and preferably has its edges inturned as at 15 to increase the rigidity of the sheet.

The respective hinge members 16 and 17, are in the nature of flat leaves 18, adapted to be secured in superimposed hinge forming relation by pintles 19. Each of these members is formed with an extension 20, preferably in the form of a plate-like portion in the plane of the leaf, which extension has an elongated slot 21. These extensions are designed to pass through suitable openings 22, formed respectively in the door and in

the corner strips, and wedge keys 23 are forced into the slots 21, bearing between the inner edge wall of the slot and the inner surface of the door or corner strip, as the case may be. The hinge members are thus rigidly held in place in a manner to permit all the usual functions of such parts, while the removal of such members is readily and conveniently accomplished when necessary.

The respective hinge members are here shown as having the extensions 20 in the same plane as the leaf portions. This is the preferred construction, as it readily lends itself to a simple and economical construction of the parts, as, for example by stamping.

While in the drawings the leaf sections are illustrated of an unequal length, it will be apparent that each of the leaves may be similarly constructed, which will materially lessen the cost of production. The leaves may be thus cast in a single mold. The outer contour of the leaves is non-essential, but it is essential that the inner edges thereof be straight and flat so that the same will properly contact with the door and with the abutment for the door. The door is locked in the usual manner, and is provided with an outwardly extending handle 32 to facilitate the opening thereof.

Having thus described the invention, what is claimed as new, is:—

1. The combination with a locker having a door, of a hinge for the door comprising leaf members having extensions to be passed through openings in the door and locker, said extensions being formed with elongated slots, and keys of wedge form entering said slots from within the locker.

2. A hinge connection for the sheet metal door of a sheet metal locker, comprising two flat lapping members pivotally associated, and extending in opposite directions from the pivot, and slotted lugs formed on the inner parallel edges of both members designed to be forced through incisions in the locker and in the door, and wedge members inserted through the slots and in contacting engagement with the inner face of the door and locker respectively.

3. A hinge construction for a sheet metal door of a sheet metal locker comprising two members having inner straight edges, said members having their inner ends lapping and pivotally connected, substantially rectangular slotted extensions on the inner par-

allel edges of the members designed to be forced through incisions in the sheet metal door and the sheet metal locker, and wedge members passing through the slots and in 5 contacting engagement with the inner walls of the door and locker.

4. A hinge for sheet metal lockers, comprising two flat members of equal thickness throughout, said members having lapping

ends which are pivotally connected and their 10 inner straight edges integrally formed with slotted extensions of the same thickness as the body of the members, and wedge members passing through the slotted extensions and in contacting engagement with the face 15 of the door and locker respectively.

In testimony whereof I affix my signature.
HARRY H. SHULTS.
